UNITED STATES PATENT OFFICE

158,598

SPUR

Arthur Leveque, Philipstown, N. Y.

Application November 15, 1949, Serial No. 6,047

Term of patent 14 years

(Cl. D38—16)

To all whom it may concern:

Be it known that I, Arthur Leveque, a citizen of the United States, residing at Philipstown, New York, have invented a new, original, and ornamental Design for a Spur, of which the following is a specification, reference being had to the accompanying drawing, forming part thereof.

I claim:

The ornamental design for a spur, as shown.
ARTHUR LEVEQUE.
